UNITED STATES PATENT OFFICE.

JAMES JOURNEY, OF NEW HOPE, CALIFORNIA.

COMBINATION STRETCHER, NECK-YOKE, AND SINGLETREE.

SPECIFICATION forming part of Letters Patent No. 614,957, dated November 29, 1898.

Application filed December 15, 1897. Serial No. 662,018. (No model.)

To all whom it may concern:

Be it known that I, JAMES JOURNEY, a citizen of the United States, residing at New Hope, in the county of San Joaquin and State of California, have invented certain new and useful improvements in a Combination Stretcher, Neck-Yoke, and Whiffletree; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to certain new and useful improvements in stretchers such as are commonly used in attaching horses or other beasts of burden to loads which they are to draw; and my object is to provide a stretcher or doubletree and singletree or whiffletree which may be easily transformed into a neck-yoke which may be cheaply constructed and easily kept in repair; and it consists in the peculiar construction, novel combination, and adaptation of parts hereinafter set forth, and particularly pointed out in the claims hereunto annexed, reference being had to the accompanying drawings, in which—

Figure 1 is a top view of my improved stretcher. Fig. 2 is a detached enlarged view of one of the combination-hooks. Fig. 3 is an enlarged detail view of one of the links.

Similar letters of reference indicate corresponding parts in all the views.

I employ a stretcher-stick 1, composed of gas-pipe of the proper size and strength and have the ends flattened for a short distance, over which ends common open links 2, such as shown in Fig. 3, are inserted and prevented from slipping off by means of pins 3, rigidly inserted in the ends of the stretcher-stick 1. To each of the links 2, at their rear ends, a bar 4 is flexibly attached by means of an eye in the end thereof, which embraces the said link 2. Such bars 4 extend rearwardly at an angle and in the same manner engage with the eye 5 of a hook 6, which is adapted to be attached to any load to be drawn. To the front end of each of the links 2 a singletree is attached by means of a metallic ring 7, from which two bars 8, similar to the bars 4, radiate, such bars 8 having eyes in their ends which engage the ring 7 aforesaid, and flat links 9, which are fitted over the flattened ends of a

stretcher-stick 10, composed of gas-pipe, such 55 links 9 being maintained in position thereon by means of a pin 11, rigidly inserted in each end thereof.

To the front end of each link 9 I attach the eye 12 of a combination hook and ring having the hook 13 as in ordinary use and a ring 14 rigidly and permanently secured to the back of such hook 13 for the purpose as will be shown.

It is often desired to use a neck-yoke when 65 at a distance in a field or on a road from a repository, and to that end I have arranged my stretchers so they may be used as a neck-yoke by detaching one of the rings 7 from the link 2, whereupon the ring 7 is inserted 70 on the end of the pole of a vehicle and the pole-straps are inserted in the rings 14, thereby providing a serviceable neck-yoke immediately.

I employ metallic stretcher-sticks instead 75 of wooden ones for the purpose of reducing the liability of breakage and becoming out of repair by reason of the action of the rays of the sun.

I am aware that stretchers have been made 80 which comprise a chain with a stick spreading the ends thereof, and that feature I do not claim, broadly; but

What I do claim as new, and desire to secure by Letters Patent, is—

1. The doubletree described comprising a stretcher-stick 1, open links secured on the ends of the same, a hook, bars interposed between and flexibly connected to the hook and open links, stretcher-sticks 10, links 9, secured on the ends of the said sticks 10, hooks attached to the links and having eyes on the backs of their shanks, rings 7 detachably connected to the open links, and rods interposed between and flexibly connected to the links 95 and rings 7, substantially as specified.

2. In a singletree a hook having an eye attached to the back of the shank thereof in connection with such singletree, all arranged and operating substantially as shown and described.

In testimony whereof I affix my signature in presence of two witnesses.

JAMES JOURNEY.
